AUTOMATIC LADLES

Earle W. Rearwin, Longmeadow, Mass., assignor to Joseph A. Kozma and Joseph A. Kozma, Jr., both of Dearborn, Mich.

Filed Jan. 9, 1961, Ser. No. 61,540

6 Claims. (Cl. 22—81)

My invention relates to a new automatic ladle for dipping molten metal from the dip well of a melting furnace and pouring into the receiving chamber of a metal casting or extruding machine, and more particularly to an improved ladle construction and automatic controls for opening same.

Heretofore, in the feeding of molten metal to casting or extruding machines, many problems have been encountered. Delays in the closing or locking of the dies or molds results in a cooling of the molten charge being held for feeding, resulting in failure to completely fill the dies or molds, or, if the metal is not poured, it will harden in the ladle. Also, delays and the inefficient methods by which the molten metal is dipped result in the formation of excessive oxides, causing poor quality of production. Moreover, experience shows that molten metal is sometimes inadvertently poured into the receiving chamber of the machine when the dies or molds are not fully closed and/or locked, and the charge of metal may cool and harden in the receiving chamber causing expensive damage and loss of the use of the machine until repaired.

An object of the present invention is to improve metal casting quality by providing an automatic ladle which will dip molten metal only from beneath the oxidized surface of the melting and/or loading furnace.

Another object of the invention is to avoid losses due to cooling of the molten metal by providing an automatic ladle with a heating means.

A further object of the invention is to improve operation of automatic ladles by providing an actuating system connected with the casting or extruding machine which will provide for rapid transfer of metal from the dip well of the melting furnace to the machine.

A still further object of the invention is to protect casting and extruding machines by providing a means for preventing pouring of metal unless the dies or molds are closed and locked.

Yet a further object of the invention is to facilitate effective operation of casting and extruding machines by providing a fully automatic ladle mechanism integrated with the operation of the machine.

For a more complete understanding of the invention, reference may be made to the accompanying drawings illustrating a preferred embodiment of the invention in which like reference characters refer to like parts throughout the several views and in which

FIG. 1 is a side view, partially in section and partially in elevation, of a preferred ladle mechanism embodying the present invention.

FIG. 2 is a top plan view of part of the mechanism shown in FIG. 1.

FIG. 3 is a cross-sectional view of the ladle taken on the line 3—3 of FIG. 1.

FIG. 4 is an electrical diagram illustrating a preferred or typical control system for the present invention.

FIG. 5 is a diagrammatic view of a preferred actuating system embodied in the present invention.

FIG. 6 is a side view, partially in section and partially in elevation, of a modified construction.

FIG. 7 is a top view of the modification of FIG. 6, and

FIG. 8 is an end view taken substantially on the line 8—8 of FIG. 6.

2

A ladle mechanism 10 is illustrated in FIGS. 1 and 2 as preferably mounted on the dip-well 11 of a melting and/or holding furnace 12 and operable to dip molten metal therefrom and pour into the receiving chamber 13 of a casting machine 14, a portion only of which is shown. Although a die casting machine is shown, it will be apparent that the invention will operate with other types of machines such as permanent mold, gravity fed machines and the like.

10 One preferred ladle mechanism 10 comprises an elongated liquid conducting structure 15 such as a trough, launder or conduit having downwardly extending flanges 16 to which is secured a rod 17 pivotally carried on upwardly extending arms 18 of a support 19, preferably mounted on the dip well structure 11. A ladle 20 is carried on one end of the structure 15 and a pouring spout 21 or the like is carried on the other end. The structure 15 is arranged to alternately dip molten metal 22 from the dip well 11 and pour it into the receiving chamber 13 of the casting machine 14.

The ladle 20 is provided with a cover 25 having a downwardly extending cup shaped portion 23a conforming generally to the contour of the ladle 20 but spaced therefrom to provide a passage 26 from the edge of the portion 23a to a slot 27, shown in FIG. 3, cut into the end of the ladle 20 at a location remote from the edge of the portion 23a.

In operation, when the ladle 20 is dipped into the molten metal 22 (called the "fill" position), the portion 30 23a pushes aside the oxides which are always present on the surface. The cover 25 prevents these oxides from entering the ladle 20, and instead, pure molten metal flows from beneath the surface through the passage 26 into the slot 27. The depth of the slot 27 regulates the amount of metal retained in the ladle 20 when same is raised.

In case the charge is not poured immediately, and also for the purpose of avoiding any cooling of the charge in flowing through the structure 15 when the pouring 40 spout 21 is lowered, a radiant heater device 30 of any preferred type (shown only in FIG. 1), is mounted on the structure 15, to furnish radiant infra-red heating to the interior thereof.

The rod 17 has on its outer end a lever arm 31 preferably actuated by a piston 32 reciprocable in a fluid cylinder 33 pivotally mounted as at 34 on a floor bracket 35. The ladle mechanism 10 is illustrated in full line in an intermediate position and in phantom lines in the fill and pour positions.

50 At each position, some part of the mechanism such as the lever arm 31 will be arranged to contact and trip a limit switch, these switches designated as LS-1, LS-2 and LS-3.

A portion only of a typical die-casting machine 14, 55 with which the ladle mechanism may be used, is illustrated as comprising a stationary die plate 40 carrying a stationary die half 41, a movable die half 42 having a cavity 43 in which is mounted a die 44. A tubular sleeve 45 is carried by the die plate 40 and provides for 60 the shot or receiving chamber 13, the molten metal being poured therein through a pouring slot 46 and subsequently forced into the die cavity 43 by a piston 47, all as is conventional with such machines.

When the movable die half 42 is closed against the stationary die half 41, a locking mechanism 49 can be actuated in conventional fashion to lock-up the machine, and when so locked, a relay designated as DL in FIG. 1 is preferably arranged to be closed for a purpose to be explained.

70 The general preferred operation of the ladle mechanism is as follows:

When the machine operator presses a switch (not

shown) to initiate closing, the ladle mechanism 10 will be simultaneously actuated to lower the ladle 20 to the fill position in the dip well 11 and when filled, will automatically raise to the intermediate position. If the lock-up switch DL is closed, the control system of the ladle mechanism 10 will operate to continue raising the ladle 20 and will lower the spout 21 to the pouring slot 46, the controlled charge of molten metal flowing from the ladle 20 through the pre-heated liquid conducting structure 15 and from the spout 21 into the receiving chamber 13. The ladle mechanism 10 will dwell at this pour position until pouring is completed and will then return to the intermediate position. After piston 47, in the case of a die-casting machine, is actuated to make the shot and the die 42 opened, a new cycle can be initiated.

In FIGS. 4 and 5, a preferred or typical control system is illustrated diagrammatically in more detail, noting that switch, relay and valve positions are shown as when the ladle mechanism 10 is in the intermediate position with the limit switch LS-2 engaged by the arm 31, and that limit switch LS-2 is a gang switch with its three switches designated as LS-2a, LS-2b, and LS-2c, in FIG. 4. Operation of the preferred circuit diagrammed is as follows:

(1) Master switch MS is closed manually.

(2) If used, pump switch PS is closed manually, energizing solenoid PR to close relay PR¹ holding the PR circuit and close relay PR² to start the pump P. This provides fluid pressure for the cylinder 33. In some installations, the user may instead use pressure from the casting machine or other source, and instead of the shown fluid operated system, an electrical or mechanical system may be employed.

(3) The casting cycle is initiated by the operator, to start the dies or molds closing and to simultaneously close relay DS, energizing solenoid 1CR through circuit having relays 2TR² and 2CR³. Energizing solenoid 1CR closes relay 1CR¹ to energize valve solenoid VL and actuate a valve 50 shown in FIG. 5, the valve shuttle 51 being moved to direct fluid pressure through a conduit 52 to the upper end of the cylinder 33. This retracts the piston 32 to lower the ladle 20 into the molten metal 22 (fill position).

(4) The ladle mechanism in the fill position engages and closes limit switch LS-3 (N.O.) to energize solenoid 2CR (1TR³ and 2TR² being closed). Energizing solenoid 2CR closes relay 2CR¹ to hold the 2CR circuit, opens relay 2CR³ to de-energize solenoid 1CR (thereby opening relay 1CR¹ and de-energizing the valve solenoid VL), and closing relay 2CR² to energize solenoid 3CR, limit switch LS-2c (N.C.) having closed on movement of the ladle mechanism 10 from the intermediate position.

(5) Energizing solenoid 3CR closes relay 3CR¹ to energize valve solenoid VR and actuate the valve 50 to direct fluid pressure through a conduit 53 to the lower end of the cylinder 33. This extends the piston 32 to raise the ladle 20.

(6) When the ladle mechanism reaches the intermediate position, limit switch LS-2c (N.C.) opens. However, if the dies or molds are locked, the lock-up relay DL will be closed, so that, relay 2CR also being closed (see step 4 above), solenoid 3CR will remain energized to keep relay 3CR¹ closed so that the ladle mechanism 10 will continue on to the pour position (see step 9 below).

(7) If the casting machine is not locked up when the ladle mechanism 10 reaches the intermediate position (in step 6 above), solenoid 3CR de-energizes, opening relay 3CR¹ to de-energize valve solenoid VR so that the ladle mechanism will remain in this intermediate position, holding limit switch LS-2b (N.O.) closed to energize a timer solenoid 1TR.

(8) On energizing timer solenoid 1TR, timer relay 1TR¹ will time out and open (unless the die or mold gets locked in the interim) to de-energize solenoid 2CR, closing relay 2CR³ to re-energize solenoid 1CR, initiating the ladle lowering cycle again (from step 3 et seq.). This

sequence of operation avoids the possible inadvertent pouring of metal into a casting machine not yet ready to operate and returns the ladle 20 to the dip well to prevent freezing of the metal in the ladle or the accumulation of excessive oxides.

(9) When the ladle mechanism 10 is actuated to the pour position, limit switch LS-1 (N.O.) closes to energize a timer solenoid 2TR, which closes relay 2TR¹ to hold the 2TR circuit, opens relay 2TR², and on timing out, relay 2TR³ opens (see step 11 below) and relay 2TR⁴ (if used) closes.

(10) Closing relay 2TR⁴ may be utilized either to signal the operator that the shot may be made or to automatically operate the die-casting piston 47, where the machine is a die-casting machine.

(11) Opening relay 2TR³ de-energizes the solenoid 2CR to close relay 2CR³ (see step 12 below) and to open relay 2CR, de-energizing the solenoid 3CR to open relay 3CR¹ and de-energize valve solenoid VR.

(12) Closing relay 2CR³ again energizes solenoid 1CR (limit switch LS-2a being closed in the pour position) closing relay 1CR¹ to energize valve solenoid VL and lower the ladle mechanism 10 to the intermediate position, where the limit switch LS-2a is again engaged and opened to de-energize solenoid 1CR once more stopping ladle operation at the intermediate position.

(13) Before a new cycle can begin (since relay 2TR² is open), the dies or molds must be opened to open relay DW, de-energizing solenoid 2TR to close relay 2TR², after which, when the operator starts the dies closed, the relay DW will close and the sequence of operation will repeat from step 3 et seq.

In FIGS. 6-8, another modification is illustrated in which a ladle mechanism 110 comprises a shortened pivotally carried liquid conducting structure 115 having a ladle 120 at one end, and a second liquid conducting structure 115A having a pouring spout 121.

A bracket 119 pivotally carries the structure 115 as at 117, and the second structure 115A is preferably pivotally carried by the bracket 119 on trunnions 123 or the like so that it may be placed and remain stationary with the spout 121 disposed in the receiving chamber of the molding machine (not shown in FIGS. 6-8). The structure 115 only is operatively connected with the cylinder 33 in this modification, so that when raised to the pour position, the molten metal flows into the stationary structure 115A and thence to the molding machine.

For convenience, switches and the heating device have been omitted from FIGS. 6-8, although operation will be substantially the same. It will be apparent that the switches LS-1, 2 and 3 shown in FIG. 1 may be located for actuation by any of the operative structure involved.

The advantage in thus dividing the conducting structure into two sections lessens the cost and increases convenience where the ladle must be replaced or changed, since only a small part of the total structure is involved.

Although I have described only one preferred embodiment of the present invention, it will be apparent to one skilled in the art to which the invention pertains that various changes and modifications may be made therein without departing from the spirit of the invention or the scope of the appended claims.

I claim:

1. An automatic ladle mechanism for transferring controlled charges of molten metal from the dip well of a furnace to the receiving chamber of a casting machine having molds selectively opened and closed and locked, said ladle mechanism comprising a support, a liquid conducting structure pivotally carried on said support to swing in a vertical plane, a ladle on one end of said structure, said ladle mechanism being provided with means selectively operable to alternately lower said ladle into and raise same from the molten metal contained in said dip well, the molten metal dipped from said dip well flow-

ing through said conducting structure to the casting machine and said ladle having means excluding oxides on the surface of the molten metal from entering said ladle when same is lowered into said dip well, said excluding means comprising a cover extending over and closing the top of said ladle and projecting outwardly and turned downwardly around the sides thereof to form a space between the ladle and the downwardly turned portion of the cover, and means openly connecting said space with the ladle under the cover.

2. The mechanism as defined in claim 1 and in which said latter means comprises a slot in the edge of said ladle remote from the edge of the downwardly turned portion of said cover.

3. An automatic ladle mechanism for transferring controlled charges of molten metal from the dip well of a furnace to the receiving chamber of a casting machine having molds selectively opened and closed and locked, said ladle mechanism comprising,

- (a) a support,
- (b) a liquid conducting structure carried on said support to swing in a vertical plane,
- (c) a ladle on one end of said structure,
- (d) actuating means operable to selectively pivot said structure to a fill position in which said ladle is lowered into the molten metal contained in said dip well, to an intermediate position in which said ladle is removed from the molten metal, and to a pour position in which said ladle is raised higher than the conducting structure so that the molten metal will flow from the ladle through the conducting structure to discharge into said casting machine and
- (e) automatic means normally operating said ladle actuating means through a cycle in sequence beginning with the intermediate position to the fill position, then through the intermediate position to the pour position, then returning to the intermediate position,

5

(f) said automatic means including means connected with said casting machine and automatically operating said ladle actuating means from the intermediate position to the pouring position only when the casting machine molds are in a locked position, and

(g) means holding said actuating means at said intermediate position if said molds are not in a locked position.

4. The mechanism as defined in claim 3 and in which 10 said holding means is automatically operable to retain said ladle actuating means in the intermediate position for a predetermined time interval if said molds are not in a locked position and to return said ladle mechanism back to the fill position if said molds are not locked within said 15 predetermined time interval.

5. The mechanism as defined in claim 4 and in which 20 said automatic means includes means automatically operable to hold said ladle actuating means in the pour position for a predetermined time interval.

6. The mechanism as defined in claim 4 and in which 25 said automatic means includes means connected with said casting machine and automatically operable each time the casting machine molds are closed to initiate the aforesaid sequence of actuation of said ladle actuating means.
